DUCTOR ROLLER ADJUSTMENT AND
METHOD

Henri E. Peyrebrune, River Forest, Ill., assignor,
by mesne assignments, to Miehle Printing Press
and Manufacturing Company, Chicago, Ill., a
corporation of Delaware

Application May 9, 1947, Serial No. 746,992

2 Claims. (Cl. 101—348)

1

The invention relates to inking mechanism for printing presses and has reference in particular to improvements in the method of and means for operating the ductor roller of said mechanism which will provide for a plurality of adjustments of said roller to control the conveyance of ink from the fountain to the ink distributing unit of the press.

More specifically, the invention concerns mechanism for actuating the ductor roller and which mechanism will include means for convenient adjustment of the pivot axis of the supporting arms for the ductor roller in order to accommodate rollers of different diameters and the method of so doing. Any variation in the diameter of the ductor roller will result in improper contact and therefore inadequate ink conveyance. Differences in roller diameter may be due to inaccuracy in manufacture or to the grinding down of the roller because of uneven surface wear or as a result of extended use in operation. Also in the purchase of composition covered rollers wherein certain diameters are specified, it very often happens that the size of the new rollers will vary to such an extent that a different setting is required to overcome the inaccuracy in the roller diameter. By the provision of means whereby the supporting arms for the ductor rollers can be adjusted so that any variation within reasonable limits in the diameter of the roller may be overcome, the practical use or life of the roller can be materially prolonged and proper ink conveyance can be obtained at all times during use.

Therefore an object of the invention resides in the provision of supporting arms for the ductor roller of inking mechanism wherein the ductor roller is eccentrically mounted on the arms for adjustment purposes and wherein the arms are eccentrically mounted in the frame of the press also for adjustment purposes so that proper contact can be obtained and maintained with respect to the fountain roller and an ink distribution drum or the like.

With these and various other objects in view, the invention may consist of certain novel features of construction and operation, as will be more fully described and particularly pointed out in the specification, drawings and claims appended hereto.

In the drawings which illustrate one preferred embodiment of the invention and wherein like reference characters are used to designate like parts—

Figure 1 is a side elevational view, parts being shown in section, of the present operating mech-

anism for the ductor roller and which is shown in associated relation with the ink fountain roller and an ink distributing drum;

Figure 2 is a partial, sectional view taken from the top of Figure 1 and illustrating the eccentric supporting and mounting means for the ductor roller, and

Figure 3 is a detail view in section of one of the eccentric bearings and adjusting means shown in Figures 1 and 2.

Referring now to the drawings, the ductor roller operating mechanism selected for illustrating the invention is disclosed in associated relation with ink fountain structure generally designated by numeral 10 and which includes the fountain roller 11, the ink fountain structure being suitably supported by the frame 12 of the inking mechanism structure. A conventional ink distributing roller or drum 13 is also shown in Figure 1, the same being journaled by shaft 14.

The ductor roller operating cam 15 may be mounted concentric with this shaft, but not to rotate therewith. The driving means for this cam is omitted because it forms no part of the present invention. However, it must be understood that on conventional presses of the class to which my invention applies, the ductor roller operating cam runs considerably slower than any of the ink distributing rollers or drums, the arrangement of the cam 15, as shown by way of example in Figure 1, must therefore be such that while it may be mounted concentric with the shaft 14, the cam 15 must be free on this shaft and driven at a speed different to the shaft.

The ductor roller 16 is adapted to have oscillating movement to alternately contact rollers 11 and 13, whereby ink is transferred from the former to the latter for distribution by a conventional ink distributing system which may include rider rollers 17, vibrating drum 18 and other rollers whereby a finely distributed film of ink is eventually applied to the printing plate on the plate cylinder, not shown.

The ductor roller 16 is carried by arms 20, the roller being journaled in said arms by eccentrically adjustable means to be presently described. The opposite ends of the arms 20 are supported by shaft 21 and secured thereto preferably by means of the pins 22, so that oscillating movement of the shaft is imparted to both supporting arms to cause oscillating movement of the ductor roller 16. Shaft 21 is journaled at its respective ends by the eccentric bearing members 23, each member being suitably mounted for rotation in the frame 12 of the fountain struc-

ture and having worm wheel teeth 24 formed in the peripheral surface of the member centrally of its width, as shown in Figure 2. The cap member 25 houses a worm gear 26 which is provided with suitable bearing studs 27 and 28 and which gear meshes with the teeth 24 of its associated eccentric member 23. The stud 28 projects beyond the cap 25 and is squared for the purpose of receiving a crank or similar tool which is thereby operatively connected with the worm gear 26. It will be seen that upon rotation of the latter by means of the squared stud 28, the respective eccentric member is rotated to adjust the location of shaft 21 and thus the pivot axis of the supporting arms 20 supporting ductor roller 16.

The cam 15 mounted to rotate freely on the shaft of the ink distributing roller 13 serves the function of oscillating the shaft 21. The means which connects shaft 21 with said cam includes a floating lever 29 supported by shaft 21 and carrying at its depending free end the cam roller 30 adapted to contact cam 15. Floating lever 29 is loose on shaft 21 and movement of the lever is imparted to shaft 21 through the medium of an actuating lever 31. Said lever 31 is suitably fixed to shaft 21 by the pin 32 and at its free depending end the lever is formed with a stop 33 adapted to contact a companion stop 34 provided on floating lever 29 at a point intermediate the ends of said lever. The actuating lever 31 is yieldingly biased in a direction toward floating lever 29 by the coil spring 35 carried by the rod 36 which is pivoted at 37 to the actuating lever 31. The opposite end of rod 36 is slidably supported by the boss 38 on the frame 12 and thus the coil spring 35 is backed by this stationary boss 38 so that its resilient tension is exerted on actuating lever 31 maintaining its stop 33 in contact with stop 34 of the lever 29 and thus maintaining the floating lever 29 with cam roller 30 in contact with cam 15.

The ductor roller 16 is provided with journaling portions 40 at each end thereof, which portions are received by the U-shaped sockets 41 comprising inwardly extending portions formed integral with its respective arm 42. The arms 42 are pivotally secured to their supporting arms 20, the former being located at the inside surface of the supporting arms and being pivotally secured thereto by the threaded pivot pins or the like 43. The position of each arm 42 on its supporting arm 20 is determined by the eccentric 44 having coacting relation with arm 42 and being carried by its supporting arm 20 through the medium of stud shaft 45. The stud shaft has a threaded extending end which receives the lock nut 46 by means of which the eccentric 44 may be locked to its supporting arm 20 in desired adjusted position whereby to locate arm 42 in its position with respect to arm 20. The said end of the stud shaft 45 is squared as at 47 for receiving a crank or similar tool whereby to effect turning of the eccentric 44 for adjustment purposes when the nut 46 is loosened.

Assuming that a new or ground down ductor roller 16 has been inserted in the U-shaped sockets 41 provided therefor and it is desired to make adjustments in the apparatus of the invention for correctly setting the ductor roller with respect to the fountain and ink distributing rollers. It will be understood of course that the ductor roller journals 40 are locked in position within their respective sockets 41 by any conventional means, not illustrated, because such

devices do not come within the scope of my invention.

A preferred procedure for setting the ductor roller consists in the following steps:

First, as viewed in Figure 1, the eccentric bearing members 23 are rotated by means of the worm 26 until the eccentricity of these members is all the way up, in other words, until the linear displacement of the ductor roller axis A from C of shaft 21 is a maximum.

A deep scribe line, not shown, extends preferably across the width of the eccentric 44 in a predetermined position with relation to other scribe lines provided on both sides of the arms 42 in which the eccentrics 44 operate.

By loosening the nuts 46 and turning the studs 45, by means of the square ends 47, these scribe lines are then brought into alignment, and the nuts 46 are tightened again. The mechanism is then in a neutral position.

The press is then advanced very slowly until the ductor roller 16 contacts the ink distributing, i.e. vibrating roller 13.

Thereupon, by means of the worms 26 and eccentric bearings 23, the ductor roller 16 is set with relation to the distributing roller 13, that is to say, the extent of contact of the ductor roller with the roller 13 is established by engaging and turning the square studs 28 of said worms.

After this contact has been established, the press is again advanced slowly until the ductor roller 16 has moved into contact with the ink fountain roller 11.

The extent of contact of the ductor roller 16 with the fountain roller is then adjusted by means of the eccentrics 44 by turning the studs 45 to the desired extent by loosening the nuts 46 and engaging the squares 47.

In operation of the ductor roller mechanism disclosed in the drawings it will be understood that rotation of cam 15 during operation of the press will cause oscillating movement of the floating lever 29, which movement is imparted to actuating lever 31 as a result of the coacting relation which these levers have through stops 33 and 34. When lever 29 is actuated in a counter-clockwise direction by the high part of cam 15 such movement is imparted to lever 31 against the tension of coil spring 35. Returning movement of lever 31 is effected by said coil spring which acts through the stops to maintain lever 29 in contact with said cam 15. The oscillating movement thus imparted to pivot shaft 21 is transmitted through supporting arms 20 to ductor roller 16 which thereby alternately contacts with fountain roller 11 and distributing roller 13 for the purpose of supplying ink from the ink fountain to said distributing roller.

It shall be understood that the usefulness of my invention is not limited to inking mechanism for printing presses, since it can be applied to any class of mechanism whereby a fluid substance is to be transmitted intermittently from a source of supply to a receiving member, nor shall the invention be restricted to constructional details of the particular embodiment thereof illustrated by the drawings, as various other forms of the device will of course be apparent to those skilled in the art without departing from the spirit of the invention or the scope of the claims.

What I claim is:

1. In an inking mechanism for printing presses, the combination of an ink supply member, an ink distributing roller system, a ductor roller for conveying ink from said member to said system,

means for intermittently actuating the ductor roller and including a supporting shaft, arms mounted on said shaft and providing bearing means for the ductor roller, a cam actuated lever also associated with said shaft to intermittently rock it together with said arms about its axis, adjustable eccentric members arranged adjacent each end of said shaft, means for actuating said eccentric members to thereby establish the effective radius of the ductor roller axis in order to vary the degree of contact of the ductor roller with the distributing roller, and additional, independently operable eccentric members associated with said arms to provide adjustable bearing means for the ductor roller to thereby vary its degree of surface contact with said ink supply member independent of the setting between the ductor roller and the distributing roller, and by maintaining the setting relation between said latter rollers undisturbed.

2. The method of accomplishing the setting of a ductor roller in an inking mechanism for proper contact relation with its associated ink supply member and ink distributing element, and wherein the ductor roller is mounted for oscillating movement by adjustable supporting means, including the steps of bringing the ductor roller

into a neutral position, in spaced relation with respect to said member and said element, establishing the desired contact relation between the ductor roller and the ink distributing element by changing the location of the ductor roller axis with respect to said supporting means, moving said roller into contact with the ink supply member, and then establishing the desired contact relation between the ductor roller and said supply member by moving the ductor roller with relation to the latter while maintaining the setting of the ductor roller with relation to said ink distributing element.
